MODULAR DISPLAY UNIT

Louis J. Corini, Philadelphia, Pa., assignor to Melbro Corporation, Philadelphia, Pa.

Filed Apr. 13, 1972, Ser. No. 243,923

Term of patent 14 years

Int. Cl. D6—04

U.S. Cl. D6—171

Fig. 2

Fig. 1

Fig. 3

Fig. 5

Fig. 4

FIG. 1 is a perspective view taken from the right rear side of a modular display unit embodying my new design;

FIG. 2 is a top view of the unit shown in FIG. 1;

FIG. 3 is a front view of the unit shown in FIG. 2;

FIG. 4 is a left side view of the unit shown in FIG. 2; and

FIG. 5 is a rear view of the unit shown in FIG. 2.

I claim:

The ornamental design for a modular display unit, as shown.
